JESSE D. STAGGS, OF LOS ANGELES, CALIFORNIA

SOUND DEVICE

Application filed December 23, 1929. Serial No. 415,903.

This invention relates to improvements in sound devices.

The general object of the invention is to provide an improved sound device for use in either reproducing sound or recording sound.

Another object of the invention is to provide a sound reproducer which includes a needle and a cone which are connected by novel mechanical means.

10 A further object of my invention is to provide a novel means for reproducing sound from a phonograph record.

An additional object of my invention is to provide a novel means for making a sound record.

Other objects of my invention will be apparent from the following description taken in connection with the accompanying drawings wherein:

20 Fig. 1 is a side elevation of my improved sound reproducer.

Fig. 2 is a section taken on line 2—2 of Fig. 1.

Fig. 3 is an end view of Fig. 1 looking 25 from the needle towards the cone.

Fig. 4 is an enlarged fragmentary section of the cone showing the means for securing it to the supporting member.

Fig. 5 is an enlarged top plan view of the 30 needle holding mechanism.

Fig. 6 is a front view of the part shown in Fig. 5.

Fig. 7 is a side view of the needle holding mechanism with parts thereof broken away to 35 more clearly illustrate the device.

Fig. 8 is a top plan view of the balsa stick used in the device.

Fig. 9 is a side view of the balsa stick.

Fig. 10 is an enlarged section taken on line 40 10—10 of Fig. 1.

Fig. 11 is a section taken on line 11—11 of Fig. 10.

Fig. 12 is a section taken on line 12—12 of Fig. 10.

45 Fig. 13 is a section similar to Fig. 11 showing a modified form of my device.

Fig. 14 is an end view of the device shown in Fig. 13, and

50 Fig. 15 is a section taken on line 15—15 of Fig. 13.

Referring to the drawings by reference characters I have indicated my improved reproducer generally at 10. This reproducer as shown is adapted to be used with records on which the sound vibrations run from side to side in the grooves but it will be understood that with slight changes in the device it may be used with records on which the sound vibrations run up and down.

As shown the device 10 comprises a needle support indicated generally at 12 and a sound cone indicated generally at 14. The needle support 12 comprises a body portion 15 having a recess 16 in one side thereof, the top of which is inclined as indicated at 17 and in the face of which is provided a conical recess 17' and the back of which is inclined as indicated at 18. On the bottom of the body 15 I provide a downwardly extending finger 19 on the rear face of which a conical recess 20 is provided.

The needle holder proper is indicated generally at 22 and includes a body portion 23 in which a needle 24 is positioned in the usual manner and retained in position by a set screw 25. The upper end of the body 23 is conically shaped as indicated at 26 and the apex thereof is adapted to be positioned in the conical recess 17' of the member 15 as clearly shown in Fig. 7.

Adjacent the lower end of the body 23 and extending rearwardly therefrom I provide an arm 27 in which is provided a recess 28 having on its rear wall a conically shaped protuberance indicated at 29, and extending downwardly from the arm 27 I provide a finger 30 while extending at right angles to the arm 27 I provide a lateral member 31 which is tapered to a point as clearly shown in Figs. 5 and 6.

The apex of the conical portion 29 of the arm 27 is positioned in the conical recess 20 of the finger 19 and adjacent the lower end of the finger 30 of the arm 27 I secure a rubber pad 32 which is engaged by a set screw 33 supported on a downwardly extending bracket 34 on the body 15.

Secured in an aperture 35 in the rear face of the bracket 34 I provide a rearwardly extending hollow tube 36 in which a rod 37 is

positioned (shown in detail in Figs. 8 and 9) and which is preferably made of balsa wood. As shown the rod 37 is preferably tapered from the center towards each end thereof and at one end of the rod I provide a flexible member 38 which is preferably made of spring steel and adjacent the outer end of member 38 there is provided an aperture 39. At the opposite end of the rod 37 I provide a needle 40 and adjacent the same end I provide a transversely extending pin 41. The flexible member 38 of the rod 37 is extended through the tube 36 at the end thereof secured to the member 12 and the point of the member 31 of the needle holder 22 is positioned in the aperture 39 of the flexible member 38 and is secured thereto as by soldering.

The end of the tube 36 opposite the member 12 is provided with opposed arms 42 which are pivotally mounted for movement about a vertical axis on pins 43 supported by lugs 44 on a block 45 which in turn is pivotally mounted for movement about a horizontal axis on pins 46 supported by arms 47 of a frame 48.

The block 45 is provided with a central aperture 49 and four screw threaded apertures 50 in each of which a screw 51 is positioned and retained in an adjusted position by a nut 52. Mounted on the screws 51 I provide wires 53 which converge towards the center of the block and are secured to an anvil 54 which includes a rearwardly projecting stem 55 and a pair of opposed lips 56. The wires 53 pass over blocks 57 which act as bridges and are movable on the block 45, being retained in position by the tension of the wires 53. The pointed end of the needle 40 of the balsa rod 37 is positioned on the anvil 54 and the anvil and the needle are retained in engagement by resilient members 58 which are in the form of a loop and are positioned on the pin 41 of the rod 37 and the lips 56 of the anvil 54. The stem 55 of the anvil 54 is secured to the apex of the cone 14 by sealing wax, glue, or in any other desired manner.

As shown the frame 48 includes a plurality of outwardly extending lugs 60 provided with apertures 61 in which screws 62 are positioned for securing the frame to a support 63.

Secured adjacent the large end of the cone 14 there is provided a strip of resilient material 64 such as chamois skin which extends beyond the edge of the cone and is clamped between the edge of the frame 48 and the support 63 for supporting the cone 14.

In operation the needle 24 is placed in position on a record and as the record rotates and the needle comes in contact with the sound producing undulations it swings from side to side on the pivotal points of the needle holder at 17', 20 and 32, thereby vibrating the arm 31 back and forth and vibrating the balsa rod 37 endwise, which vibrations are

transmitted through the needle 40 to the anvil 54 and thence through the stem 55 to the cone 14.

In tuning the device the wires 53 are tightened to such a degree as will cause the entire cone to vibrate on the deep base notes and the bridges 57 may be moved to the positions wherein the best results are obtained.

As the grooves in the record move the needle 24 to and fro, and vibrates the cone 14, the wall of the groove pushing against the side of the needle must overcome the inertia of the cone and parts when moving in one direction, and when stopping it to move it to the opposite direction the greatest strain comes on the wall of the groove. At ordinary speeds of vibration of a few hundred a second the inertia of the cone and moving parts is great enough to break down the sides of the grooves and ruin the reproduction and the record.

In my device the wires 53 hold the needle 24 in the center of the groove until they are pushed to one side, then the wires help to arrest the inertia and tend to pull the cone 14 back to its original position. Therefore, for a given pitch the tension on the wires can be adjusted so as to balance the inertia of the cone and moving parts.

In a cone speaker only portions of the cone 95 vibrate for different tones. On a low tone the whole cone will vibrate and on a higher tone only a part of it nearest the apex of the cone will vibrate, the rest of the cone remaining stationary and assisting the wires 53 to 100 return the vibrating portion to a neutral position.

As the cone is the largest mass this assists materially for the wires can be tightened to balance the whole cone on the lower notes. 105 If a tone of higher pitch is reproduced the weight to be vibrated is reduced for only a section of the cone will vibrate and the tension on it is increased by the stationary part of the cone plus the tension of the wires. 110 Therefore the cone may be approximately balanced for the audible notes. This very materially reduces the wear on the record and the power required to vibrate the cone and further produces a full range of tones which 115 are sweet and without accompanying mechanical sound.

In Figs. 13, 14 and 15 I have indicated a modified form of my device generally at 65. 120 This device is particularly adapted for use with radios but may be used in connection with any device wherein it is desired to transform electrical impulses into sound waves. As shown the device 65 includes a cone speaker 66 similar to the cone speaker 14, a frame 67 similar to the frame 47, and a block 68 similar to the block 45, except that the frame 67 includes a cross member 69 and the block 68 is rigidly secured to the frame by screws 125 130

70 instead of being pivotally secured there-to as is the block 45.

The block 68 is provided with a central aperture 71 and four screw threaded apertures 72 in each of which a screw 73 is adapted to be positioned and retained in an adjusted position by a nut 74. Mounted on the screws 73 I provide wires 75 which converge towards the center of the block where 10 they are secured to an anvil 76 which is made of gray iron and is adapted to act as the core of a solenoid 77. The wires 75 pass over blocks 78 which act as bridges and are movable on the block 68, being retained in position by the tension of the wires 75. The anvil 76 is provided with a stem 79 which is secured to the apex of the cone 66 by sealing wax, glue, or in any other desired manner.

In operation the solenoid 77 is electrically 20 connected to the device which produces the electrical pulsations and as the device operates the varying current to the solenoid 77 causes the anvil 76 to move against the tension of the wires 75 and through the medium 25 of the stem vibrates the cone 66 thereby producing audible sounds. The device 65 is tuned and adjusted in the same manner as previously described in connection with the device 10.

30 Although I have described my invention as applied to a phonograph or radio it will also be understood that it can be embodied in connection with talking pictures without departing from the features of my invention.

35 What I claim is:

1. In a sound reproducer, an amplifier, a support, an anvil, tension members on said support and supporting said anvil, means to vibrate said anvil, and means to connect said 40 anvil to said amplifier.

2. In a sound reproducer a needle support, an amplifier, a needle holder on said needle support, means to mount said needle holder to pivot about two spaced, fixed, pivot points 45 on said support and means engaging said needle holder to transmit longitudinal vibration to said amplifier.

3. In a sound reproducer, a block, a frame, said block being supported by said frame, a 50 cone speaker, a support, said frame being mounted upon said support, an anvil, means to impart movement to said anvil, tension means to secure said anvil to said block and means on said anvil to secure it to said cone.

55 4. In a sound reproducer, an amplifier, means to support said amplifier, a stem on said amplifier for actuating the same, means to move said stem to actuate the amplifier, a plurality of tension members, means to connect said tension members to said stem to support the same and means to support said members under tension.

60 5. In a sound reproducer, a supporting block, an anvil, a needle adapted to be vibrated by a phonograph record to move said

anvil, a plurality of supports on said block, a wire secured to each of said supports, said wires converging towards the center of said block and being secured to said anvil, bridges interposed between said supports and said anvil, said wires passing over said bridges, an amplifier, means to support said amplifier and a stem on said anvil and secured to said amplifier.

6. In a sound reproducer, a block, a frame, said block being supported by said frame, a cone speaker, a support, means to secure said frame to said support, an anvil, means to impart movement to said anvil, a plurality of supports on said block, a wire secured to each of said supports, said wires converging towards the center of said block and being secured to said anvil, and a stem on said anvil, said stem being secured to said cone.

7. In a sound reproducer, a needle support, a cone speaker, a needle holder associated with said support, said needle holder comprising a body portion having means to secure a needle to one end, the opposite end of said body being conically shaped and the apex of said conical portion being positioned in a recess in said needle support, a rearwardly extending arm on said body, a conical portion on said arm, a downwardly extending boss on said support, said boss having a recess, said conical portion being positioned in said recess, a downwardly extending finger on said arm, a resilient pad adjacent the lower end of said finger, a set screw supported by said needle support, one end of said set screw engaging said pad, a lateral member on said arm, said lateral member extending transversely from said needle holder and means connecting said lateral member and said cone.

8. In a sound reproducer, a needle support, a hollow tube, one end of said tube being secured to said support, a cone speaker, a rod positioned in said hollow tube, a flexible member extending from one end of said rod, said needle holder secured to said flexible member, a needle extending from the opposite end of said rod, an anvil, said needle engaging said anvil, means to retain said needle in engagement with said anvil, and a stem on said anvil, said stem being secured to said cone.

9. In a sound reproducer, a block, a frame, said block being supported by said frame, a cone speaker, a strip of resilient material adjacent the large end of said cone, said material extending beyond the edge of said cone, a support, means to secure said frame to said support, said resilient material being clamped between said frame and said support, an anvil, means to impart movement to said anvil, a plurality of adjustable supports on said block, a wire secured to each of said supports, said wires converging towards the center of said block and being secured to said anvil, movable bridges interposed between said adjustable supports and said anvil, said wires pass-

- ing over said bridges, a stem on said anvil and said stem being secured to said cone. 75
10. In a sound reproducer, a needle support, a cone speaker, a needle holder associated with said needle support, said needle holder comprising a body portion having means to secure a needle to one end, the opposite end of said body being pointed and the apex of said point being positioned in a recess in said arm and said conical portion being positioned in a recess in a downwardly extending boss on said support, a downwardly extending finger on said arm, a resilient pad adjacent the lower end of said finger, a set screw supported by said needle support, one end of said set screw engaging said pad, a member on said arm, said member extending transversely from said needle holder and means connecting said member and said cone. 80
11. In a sound reproducer, a needle support, a hollow tube, one end of said tube being secured to said support, a frame, means to mount the other end of said tube for universal movement on said frame, a cone speaker, a support, means to secure said frame to said last support, a needle holder associated with said needle support, and mounted relative thereto, said needle holder comprising a body portion including means to secure a needle thereto, a rod positioned in said hollow tube, said needle holder being secured to said rod, a needle extending from the opposite end of said rod, an anvil, said needle engaging said anvil, and a stem on said anvil secured to said cone. 85
12. In a sound reproducer, a needle support, a hollow tube, one end of said tube being secured to said support, a pair of opposed arms adjacent the opposite end of said tube, a block, an aperture in said block, said tube arms being pivotally secured to said block for movement about a vertical axis, a frame, said block being pivotally secured to said frame for movement about a horizontal axis, a cone speaker, a strip of resilient material adjacent the large end of said cone, said material extending beyond the edge of said cone, a support, means to secure said frame to said support, a needle holder associated with said needle support, and mounted relative thereto, said needle holder comprising a body portion including means to secure a needle thereto, a rod positioned in said hollow tube, a flexible member extending from one end of said rod, a portion of said needle holder being secured to said flexible member, a needle extending from the opposite end of said rod, an anvil, said needle engaging said anvil and resilient means to retain said needle in engagement with said anvil, a plurality of adjustable supports on said block, a wire secured to each of said supports, said wires converging towards the center of said block and being secured to said anvil, bridges interposed between said adjustable supports and said anvil, said wires 90
- passing over said bridges and a stem on said anvil, said stem being secured to said cone. 95
- In testimony whereof, I hereunto affix my signature.
